(57) **CLAIM**

The ornamental design for a handle for electric toothbrush as shown and described.

DESCRIPTION

FIG. 1 is a front, right and top perspective view of a handle for electric toothbrush showing my design;

FIG. 2 is a rear, left and bottom perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is an enlarged top plan view thereof;

FIG. 8 is an enlarged bottom plan view thereof; and,

FIG. 9 is an enlarged view of portion 9 shown in FIG. 2. The dash-dash broken lines depict portions of the article that form no part of the claimed design. The dot-dash broken lines seen in FIGS. 2 and 9 are for the purpose of depicting enlarged view indicators that form no part of the claimed design.

1 Claim, 9 Drawing Sheets
